UNITED STATES PATENT OFFICE.

SAMUEL TUCKER, OF WABASH CITY, INDIANA.

IMPROVEMENT IN SHEEP-HOLDERS.

Specification forming part of Letters Patent No. 135,175, dated January 21, 1873.

To all whom it may concern:

Be it known that I, SAMUEL TUCKER, of Wabash City, in the county of Wabash and State of Indiana, have invented a new and useful Improvement in Sheep-Holder, of which the following is a specification:

The object of this invention is to provide convenient and effectual means for holding sheep while they are being sheared; and it consists in a frame or holder attached to the table or bench, so constructed that the legs of the sheep are secured by clamp-bars while the sheep lies upon the table on its side, the construction and arrangement of parts being as hereinafter more fully described.

In the accompanying drawing, Figure 1 represents a vertical longitudinal section of the holder attached to the table. Fig. 2 is a top view of the holder.

Similar letters of reference indicate corresponding parts.

A represents a table, bench, or plank, upon which the sheep is laid and to which my sheep-holder is attached. B is a bar or bed-piece set on edge, to the ends of which are attached the head-pieces C C, having foot-pins D D, by means of which the holder is attached to the table, as seen in Fig. 1. E E represent upright pieces attached to the sides of the bar B, and extending, like the heads C, above the bar, and forming jaws, as seen in Fig. 2. F F

are clamps pivoted to the pieces E E. G G are springs by which the clamps F are raised. H H are recesses or gains cut in the top of the holder-bar B.

In using the holder the sheep is laid on the table A, and his feet are confined in the recesses H H by bringing around the clamp-bars F F and fastening them to the head-pieces, as seen in Fig. 1. This fastening is done by means of the springs I I and pins J J, or by either mode, as may be deemed necessary.

The advantage of my invention is that the sheep, when confined in this manner, is powerless to move, and the operation of shearing is performed without interruption, and, consequently, with dispatch.

Having thus described my invention, I claim as new and desire to secure by Letters Patent—

1. An apparatus for holding sheep when being sheared, consisting of the bed-bar B, head-pieces C C, uprights E E, clamps F F, and recesses or gains H H, substantially as set forth.

2. The springs G G, fastening-wires I I, and pins J J, in combination with the bed-bar B and clamps F F, as and for the purposes described.

SAMUEL TUCKER.
